UNITED STATES PATENT OFFICE

150,213

DESIGN FOR A FISHING REEL

Lucian Denys, Detroit, Mich., assignor to Hautau Tuynman Company, Detroit, Mich., a corporation of Michigan

Application October 19, 1946, Serial No. 134,069

Term of patent 7 years

(Cl. D31—4)

To all whom it may concern:

Be it known that I, Lucian Denys, a citizen of the United States, residing at Detroit, county of Wayne, and State of Michigan, have invented a new, original, and ornamental Design for a Fishing Reel, of which the following is a specification, reference being made to the accompanying drawing, forming part thereof.

Fig. 1 is a perspective view of a fishing reel embodying my new design.

Fig. 2 is a top plan view thereof.

I claim:

The ornamental design for a fishing reel, as shown.

LUCIAN DENYS.
